(57) **CLAIM**

The ornamental design for a dustpan, as shown and described.

DESCRIPTION

FIG. 1 is a top front perspective view of an embodiment of a dustpan showing our new design;

FIG. 2 is a top rear perspective view thereof;

FIG. 3 is a bottom rear perspective view thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a right side elevational view thereof;

FIG. 9 is a left side elevational view thereof;

FIG. 10 is a top rear perspective view thereof and showing the dustpan in a folded storage position; and,

FIG. 11 is a cross-sectional elevational view thereof taken along line 11-11 in FIG. 6.

The broken lines showing portions of the dustpan in the drawings form no part of the claimed design.

1 Claim, 9 Drawing Sheets
